[57] CLAIM

The ornamental design for a combination fan and novelty item, as shown and described.

DESCRIPTION

FIG. 1 is a front elevational view of a combination fan and novelty item showing my new design;

FIG. 2 is a top view thereof;

FIG. 3 is a bottom view thereof; and,

FIG. 4 is a right side elevational view thereof.

The left side elevational view is identical to the right side elevational view.

The rear elevational view is identical to the front elevational view shown in FIG. 1.
